WARDROBE CASE

Arthur Burger, New York, N. Y.

Application December 28, 1935, Serial No. 56,582

4 Claims. (Cl. 190—41)

This invention relates to luggage and particularly to wardrobe cases in which a clothes rack is adapted to be folded into and supported by the case or to be held upright thereby for hanging clothes upon or removing them from the rack. The invention also relates to clothes racks adapted for use in wardrobe cases. More particularly the invention relates to wardrobe cases in which a clothes rack is adapted to be held rigidly in an upright position for placing or removal of clothes thereon and at the same time may be readily pivoted to a horizontal position and/or to an inverted position in the cover of the case.

One object of my invention is to provide fittings for wardrobe cases which are extremely simple and inexpensive as compared with others in use before my invention and which will be easier to use and entirely out of the way when not in use.

Another object of my invention is to provide wardrobe cases having racks upon which clothes may be hung more easily than they could be packed in an ordinary suitcase, can be kept in better condition when packed and can be readily removed and hung up when the case is opened without unpacking the entire case.

Another object of my invention is to provide a wardrobe case in which a clothes rack may be held securely in upright position for packing or in a position longitudinal of the case when it has been packed and closed, and can be removed entirely for hanging in a closet or elsewhere.

Another object is to provide a wardrobe case in which the rack is mounted so that it is inverted in shifting from the position for packing to the position for carrying and has means for folding the skirts smoothly during this inversion.

In the accompanying drawings I have given several illustrations of my invention and suggested certain modifications thereof. These are not intended to be exhaustive and should not be taken as limiting of the invention but are given rather with a view to illustrating and explaining the invention and principles thereof so that others skilled in the art may utilize my invention in numerous forms and varying embodiments according to the requirements of each particular use.

Fig. 1 is a perspective view of a wardrobe case embodying my invention with the clothes rack in upright position ready for placing or removal of clothes therefrom.

Fig. 2 is a cross section of the same embodiment as shown in Fig. 1, but with the clothes rack in a horizontal position.

Fig. 3 is a fragmentary sectional view similar to Fig. 2 but with the clothes rack inverted into the cover of the case and with the curtain placed over the rack.

Fig. 4 is a view in elevation of a bracket which may be used instead of that shown in Figs. 1, 2 and 3.

Fig. 5 is a perspective view partially broken away of another case embodying my invention in a different form.

Fig. 6 is a view in cross section of the embodiment shown in Fig. 5 but with the clothing rack in the process of being inverted into the cover of the case.

Fig. 7 is a perspective view of still another embodiment of my invention.

Fig. 8 is a view in elevation of the bracket used in Figs. 1 to 3.

Fig. 9 is a section along line 9—9 in Fig. 8.

Referring first to Figs. 1 to 3 inclusive, I have shown a case consisting of a box 10 having a cover 11 hinged thereto. A clothing rack 12 is shown mounted in upright position in the brackets 13.

This clothes rack 12 may be a simple frame having at its top any suitable means, e. g., the folding rails 14, 15 for holding clothes hangers 16 and at its bottom a cross bar 17 adapted to hold the skirts of garments which are hung on the hangers 16 and to fold them smoothly when the rack is inverted into the cover as will hereafter be described.

The particular construction of this rack 12 is not essential to my invention in its broader aspects. As shown, the cross bar 18 is made U shape so that its perpendicular ends form rails under which the ends 19 of the hanger 16 engage to lock the hangers against removal when they are on the rails 14. Each rail 14 is secured at one end to the cross bar 18 and near its other end to the bracket 20. The rail members 15 are pivoted to the rail members 14 and their inner ends extend beyond the pivot and are rounded or pointed so as to snap into the grooves 21 in the end of the cross bar 18. Thus the rail members 15 when folded to a perpendicular position are latched in that position and serve to lock the hangers 16 in place on the rails 14.

At the bottom ends of the frame 12 are studs 25 and 26 adapted to engage in the bracket 13 (best shown in Figs. 2 and 3). A stud 25 engages in the upper vertical slot of the bracket 13 and serves as a bearing and pivot upon which the rack 12 is supported in the position shown in Figs. 55

- 1 and 2 and upon which it may be swung from the position shown in Fig. 1 to that shown in Fig. 2. The stud 26 engages the bracket 13 in the lower slot 27 which is substantially horizontal or longitudinal with the bottom of the case. The bottom of this slot as shown has a depression in which the stud 26 engages to lock the rack in upright position.
- 10 At the corners of the cross bar 18 are other studs 28 which engage in the slot 29 of the bracket 30 secured in the cover near the hinge edge thereof. These studs also serve as pivots upon which the rack is swung from the position shown in Fig. 2 to that shown in Fig. 3.
- 15 Brackets 31 having spring latches associated therewith are secured near the opposite ends of the cover and engage the projection 32 on the rack 12 to hold it in position in the cover.
- 20 A curtain 34 is secured to the front of the cover and at its bottom is provided with snap fasteners 35 adapted to be secured to the snaps 36 on the cross bar 18, whereby this curtain may be drawn over the rack 12 and the clothes hung thereon when the rack is positioned in the cover.
- 25 This is shown in Fig. 3.
- 30 In the use of this case the cover 34 is first thrown back out of the way as shown in Figs. 1 and 2. The rack 12 is then pulled down from the cover to the position shown in Fig. 2, where it rests upon the four studs 28 and 25 in the slots of the brackets 30 and 13. The top of the rack is then lifted from the bracket 30 to the upright position shown in Fig. 1, whereupon the studs 26 enter the slots 27 and, as the rack reaches the upright position, fall into the depressions or notches in the bottoms of the slots and thus lock the rack in its upright position. The rails 15 are then folded out to the position shown in Fig. 1, and the hangers 16 may be pulled out onto these rails and removed if desired. When the clothes are put upon the hangers the hangers will be pushed back onto the rail 14 the rail member 15 then swung inwardly to the perpendicular position in which they are held by means of the grooves 21. The rack 12 is lifted sufficiently to raise the studs 26 out of the depressions in the slots 27 and is then swung back to the position shown in Fig. 2. In this position the clothes, as represented by the dress 37 will extend smoothly from the hanger 16 over the cross bar 17 and over the front edge of the box 10. The bottom of the rack 12 is then lifted from the position shown in Fig. 2 into the top, i. e., to the position shown in Fig. 3. As this is done the skirts of the clothing fold naturally and smoothly across the cross bar 17 and fall on the back of the rack 12. The rack is finally snapped into the bracket 31 and the curtain 34 is drawn down over the rack and secured in place by the snap fasteners 35 and 36.
- 40 The bracket 13 is particularly important in this example. It is small and out of the way when the case is being packed; it will not catch the clothes; and it is extremely inexpensive; yet it serves efficiently to lock the rack in the case in an upright position and it serves as a bearing for the pivoting of the rack to its horizontal position. The lower slot 27 by engaging the stud 26 locks the rack against vertical movement and the notch in its bottom engages the stud to lock the rack against pivotal movement. Yet when the rack is lifted to bring the stud 26 against the top of the slot 27 it is easily pivoted on the stud 25 and thus lowered to a horizontal position in which the stud 26 is automatically released from the slot 27.

This bracket 13 is not limited to the particular form shown in these figures, but may be substantially varied, e. g., as shown in Fig. 4.

In the form of the invention shown in Figs. 5 and 6 the box 10 and the cover 11 are substantially the same as those shown in the figures already discussed. The frame 12a is also similar to the frame 12. In this case, however, instead of the upper cross bar 18 a somewhat different cross bar 18a is provided and instead of the rails 14 the U-shaped rails 14a are provided, the free ends of which serve to engage the ends 19a of the hangers 16a to lock them in place in a manner similar to that achieved by the perpendicular ends of the cross bar 18 in Fig. 1. The rail members 15a are pivoted on the members 14a and, as in Fig. 1, these serve to lock the hangers 16a in position. In this case the slotted heads 23a snap over the rail 18a to latch the rails 15a in this perpendicular position.

In this embodiment of the invention, however, a supplementary frame 40 takes the place of the upper studs 28, the lower studs 26 and the slots 27 and 29 all shown in Fig. 1, in that it provides both for locking the clothes rack in the upright position and for pivoting the rack when it is inverted into the cover. This supplemental frame 40 is pivoted to the rack 12a at its upper end at 41 and the opposite end of the supplemental frame is pivoted in the cover at 42. One of these pivots, preferably the pivot 42, is removable, e. g., by flexing the ends of the frame 40 over the pivot studs on which they swing. Thus the entire frame can be removed from the case for hanging in a closet, etc., as in the case illustrated in Fig. 1.

In the use of this case as shown in Figs. 5 and 6 the rack 12a is released from the latch 31a in the cover and is swung out to the position shown in Fig. 1 wherein the studs 25 are held in the brackets 13a. In this position the upper end of the rack 12a is held by the frame 40 rigidly against falling in either direction. The arms 15a are swung out and the hangers removed and used exactly the same as already described in connection with Fig. 1. When the clothing is in place the hangers 16a are put back onto the rails 14a, the members 15a are swung to the perpendicular position and snapped over the rail 18a and finally the studs 25 are lifted out of the brackets 13a and the rack 12a is swung to the inverted position and latched in the cover by means of the latch 31a. Fig. 6 shows the rack in the act of being swung into the cover. As shown in this figure the skirts of the clothing on the rack fall smoothly over the cross bar 17a as has already been described with Figs. 1 to 3 and fall down over the back of the rack 12a. With the rack placed in the cover the curtain 34 is drawn down over the rack and secured by means of the snap fasteners 35, 36.

In Fig. 4, I have shown a bracket 13b which may be used in place of the bracket 13 shown in Figs. 1 to 3. In this case a right angled slot is provided and the bracket is used with a broad flat stud 25b shown in cross section in this figure. This stud, e. g., as shown in Fig. 7 may be an extension of the cross bar 17c. With the rack 12 in the position shown in Fig. 2 the studs 25b will lie in the broad shallow portion of the slots. When the rack is swung to upright position, however, the studs will fall into the vertical portion of the slots and there will hold the rack rigidly against falling in either direction. The hook 44 serves as a stop to keep the stud 25b from pulling

entirely away from the bracket 13b when the rack is lifted to release the stud from the vertical slot.

In Fig. 7 I have shown a Gladstone type of case. In this case since the cover is normally used for packing it is not practicable to fold the clothes rack into the cover as in the other case shown. In this case, therefore, brackets 30c are provided at the back of the box portion 10c and brackets 13b are provided near the front exactly as in the case illustrated in Fig. 1. The clothes are hung onto the hangers and the hangers mounted on the rack 12c while the rack is in the upright position shown in Fig. 7. When they are thus in place and suitably locked the rack is lifted to release it and swung back to the horizontal position, after which the front end is lifted to fold the skirt under the cross bar 17c and is then dropped again into the bracket 13b. The flexible partition or cover 34c is then brought down over the rack and secured in place by the snap fasteners 35c, 36c.

The rack 12c used in this case is again somewhat different from those shown in the other cases. Here as before, however, the particular form is not essentially dependent upon the other features discussed and the special features of each of these racks might be used interchangeably. In this case the rack is particularly designed for holding men's clothes rather than women's clothes as are the racks illustrated in Figs. 1 and 5. The upper cross bar 18c in this case forms a clothes loop and instead of supporting the hangers 16c on side rails they are hung directly upon the cross bar 18c. A depression 45 is formed in the center of each side of the cross bars 18c and adjacent the depression is a gate slide 46, the motion of which is limited by the stud 47 acting in the slot 48.

To place or remove one of the hangers 16c the slide 46 is drawn back away from the depression 45 and the hook 49 of the hanger 16c is placed in or removed from the depression. After the hanger is placed and the rack is otherwise ready for folding down into the case the slide 46 is moved so as to extend across the depression 45 and lock the hook 49 therein.

With these cases and racks embodying my invention as described above or in any of the numerous forms in which my invention may be embodied clothes may be packed easily and expeditiously and are kept fresh and are protected against crushing and the racks are held securely while they are in use.

What I claim is:

1. A wardrobe case comprising a bottom portion, a cover hinged thereon and a clothes rack adapted to fit into the cover with clothes folded thereon and to hold the clothes hanging therefrom when it is held upright, studs on the sides of the rack near its top, adapted to hold the top end of the rack in the back of the cover, studs on the sides of the rack near its bottom adapted

to hold it in the front of the bottom portion and a latching stud near at least one of the studs at the bottom of the rack; brackets in the cover at opposite sides near each of its four corners adapted to position the rack in the cover, the 5 brackets near the hinge being slotted in a direction longitudinal of the cover so that with the cover open the studs may be inserted downwardly therein and the brackets near the front of the cover having spring latch members to hold 10 the rack removably therein, and brackets near the front of said bottom portion having slots transverse to the bottom adapted to receive the studs near the bottom of the rack and at least one of said brackets on the bottom portion having 15 a second slot transverse to the first and with a notch in its bottom adapted to receive the latching stud and thereby to hold the rack in upright position against collapsing in either direction.

2. A wardrobe case comprising a bottom portion and a cover hinged thereon, a clothes rack having a stud at each side near the top thereof, and a bearing stud on each side of the rack near the bottom thereof, and an auxiliary stud on the side of the rack near the bottom thereof spaced 25 a short distance from one of the bearing studs near the bottom, a bracket on the cover at each side near its hinge end, slotted longitudinally of the cover for reception and removal of one of the studs at the top of the rack, a bracket near at 30 least one side of the opposite end of the cover adapted to hold the rack in the cover, a bracket on the bottom portion near the front at each side thereof, each having a slot transverse and at least one having another slot longitudinal of 35 the bottom, said longitudinal slot being notched on its bottom side to latch the auxiliary stud therein by gravity.

3. A clothes rack for a wardrobe case comprising a frame, clothes hangers carried at the top 40 of said frame, a stud at each side of the frame near the bottom thereof, another stud at at least one side of the frame near but spaced from the first-named stud and brackets for supporting said rack positioned to engage said studs, each 45 having a slot into which the first-named studs may be inserted and adapted to position said studs against horizontal lateral movement and at least one of said brackets having another slot adapted to receive said other stud and to position 50 it against horizontal lateral movement.

4. A clothes rack as defined in claim 3 in which one slot is vertical and the other horizontal with a notch in its bottom and its entrance spaced from the bottom of the first by a distance equal 55 to the spacing of the studs whereby when one stud is positioned in a vertical slot the rack may be rotated about that stud as a pivot to bring the other stud into its slot and eventually to engage it in its notch.

ARTHUR BURGER.
